DESIGN FOR EYE SPECTACLES FOR CHICKENS OR THE LIKE

Daniel Eisen, New York, N. Y.

Application August 18, 1942, Serial No. 107,956

Term of patent 7 years

To all whom it may concern:

Be it known that I, Daniel Eisen, a citizen of the United States and residing at New York city, in the county of New York and State of New York, have invented a new, original, and ornamental Design for Eye Spectacles for Chickens or the like, of which the following is a specification, reference being had to the accompanying drawing, forming part thereof, and in which

Fig. 1 is a front view of the eye spectacles for chickens or the like showing my new design,
Fig. 2 is a top plan view thereof, and

Fig. 3 is an end elevation, the engaging means shown in broken lines in Figs. 1 and 2 having been omitted.

My design for eye spectacles for chickens is characterized by the specific configuration of the nose bridge and the placement of the same in its relation to the upright lens element.

I claim:

The ornamental design for eye spectacles for chickens or the like, substantially as shown and described.

DANIEL EISEN.
